CASH REGISTER

Edward W. Herman, Dayton, Ohio, assignor to
 The National Cash Register Company, Dayton,
 Ohio, a corporation of Maryland

Application June 16, 1934, Serial No. 730,868

10 Claims.

(Cl. 235—6)

This invention relates to improvements in cash registers or accounting machines of the key-operated type and is more particularly related to improvements in locking mechanism for controlling the automatic selection of totalizers and their associated devices for operation.

One of the several objects of this invention is to provide novel means for automatically selecting one totalizer for actuation when another totalizer is locked against such action.

Another object is to provide means for automatically selecting one totalizer and its associated devices for actuation when another totalizer and its associated devices are locked against such operation.

A further object is to provide a plurality of lock-controlled devices, one for each totalizer selecting key, for locking against operation any selecting key and its corresponding totalizer and associated devices, and to thereby effect the automatic selection of another totalizer and its associated devices for operation.

A still further object is the provision of a separate locking construction, comprising adjustable means under control of lock and key, which means when moved to a certain one of its various positions of adjustment releases the locked totalizer selecting keys and simultaneously effects the automatic selection of a certain one of said totalizers and its associated devices for operation.

Another specific object is to provide means for operating the machine on an automatic "open keyboard" with respect to registering in one totalizer, and on an optionally "open keyboard" with respect to registering in another totalizer.

With these and incidental objects in view, the invention includes certain novel features of construction and combinations of parts, the essential elements of which are set forth in appended claims, and a preferred form of embodiment such as hereinafter described with reference to the drawings which accompany and form part of the specification.

45 Of said drawings:

Fig. 1 is a side view of the machine, taken just within the left-hand side frame and looking toward the right, showing the lock-controlled devices for locking the totalizer selecting keys against operation, and the adjustable means for releasing the locked keys.

Fig. 2 is a rear view of a portion of the releasing mechanism for the cash drawers.

Fig. 3 is a top plan view of part of the mechanism shown in Fig. 2.

Fig. 4 is a side view of the special counters and their actuating means.

Fig. 5 is a detail side view of the "A" totalizer lock and the means actuated thereby for effecting the automatic selection of the "B" totalizer and its associated devices.

Fig. 6 shows the single lock control mechanism and its control of the A and B keys.

Fig. 7 shows the clerks' type wheel and the means controlled by the "B" clerk's key for adjusting it to print the character corresponding to said key.

Fig. 8 is a side view of the "B" totalizer engaging mechanism.

Fig. 9 is an illustration of the mechanism for normally automatically engaging the "A" totalizer for operation.

Fig. 10 is a top plan view, partly broken away, showing the general location of the lock-controlled devices for locking the totalizer selecting keys against operation, and the adjustable means for releasing said locked keys.

Fig. 11 is a detail side view of the "B" special counter and the means for preventing the actuation of the "A" special counter.

Fig. 12 is a detail of the cam plate partially shown in Fig. 9.

General description

The present invention is shown applied to a key-operated type of cash register, such as fully shown and described in United States patents granted to Charles W. Green, Nos. 1,707,188, 1,842,546 and 1,920,374, issued March 26, 1929, January 26, 1932, and August 1, 1933, respectively. Only such parts of the machine as are directly involved in the present invention will be described herein, as reference may be made to the patents mentioned for any detailed information concerning the construction and operation of the rest of the machine.

While this invention has been shown applied to a cash register of the type illustrated and described in the above cited patents, it is to be understood that the invention is capable of being applied to or embodied in other forms of cash registers and accounting machines without departing from the spirit of the invention.

As is shown in the patents above referred to, machines of this type have previously been provided with a plurality of totalizers adapted to segregate the transactions entered in the machine according to separate departments, classes or clerks. Usually one of the totalizers is normally set for operation so that when the amount

keys alone are depressed the amount will be recorded in the normally operative totalizer, and the printing element, indicator, special counter and cash drawer associated with said totalizer 5 will be operated accordingly. In order to select any other totalizer for operation there is generally provided a special selecting key for that totalizer, depression of which key serves to disable the mechanism which normally causes the engagement of the normally operative totalizer and simultaneously adjusts for engagement the selected totalizer and its associated devices.

Such machines are sometimes provided with a plurality of selecting keys, one for each totalizer. 15 While it is not essential that such a key be provided for each totalizer, especially where one of the totalizers is normally set for operation, it is found desirable to do so primarily for the purpose of lifting the key coupler to the coupling 20 position so that the amount keys can be attached thereto successively as desired. By a careful manipulation of one or more of the amount keys the key coupler can also be lifted to this particular position to attach other amount keys 25 to the coupler, but there is nothing to prevent the movement of these keys beyond the coupling point or to serve as a stop when this point is reached. It is often desirable, therefore, to provide a separate selecting key for each totalizer 30 so that when it is operated the coupler will be positively stopped at the coupling position and will not be lifted beyond this point, such as would be the case if an amount key were operated too quickly.

35 There has been also employed in such machines special lock-controlled devices, one for each totalizer selecting key, adapted to selectively lock against operation any selecting key and its corresponding totalizer without interfering 40 with the usual operation of any other totalizer, and the provision of mechanism, comprising adjustable means under control of lock and key, whereby the proprietor or other authorized persons can conveniently render ineffective said 45 lock-controlled devices for the totalizer selecting keys.

The present invention includes all of the above mentioned features in combination with novel means for effecting the automatic selection of 50 any one of a plurality of totalizers and its associated devices for operation.

For the purpose of illustration, the present invention is shown applied to a machine provided with two totalizers. These totalizers are 55 so arranged that either one or the other may be brought into operative relation with the operating means, so that the clerks may register the amounts of their sales independently. It is, moreover, desirable that either one of the totalizers be capable of being engaged automatically 60 whenever any of the amount keys alone are operated, and that the other totalizer be placed in operation under the control of its respective selecting or clerk's key which is operated in conjunction with the desired amount keys. It is also desirable that means in the form of special transaction keys be provided for throwing out or disengaging the totalizer which has previously been selected for operation.

70 In the present embodiment of the invention the upper totalizer has been appropriated to receive the amounts registered by the "A" clerk, while the lower or remaining totalizer is placed under the control of the "B" clerk.

75 While it is only essential that one clerk's key

be provided in the present machine, since the totalizer assigned to clerk "A" is normally set for operation, a separate clerk's key has been provided for each totalizer in order to facilitate the lifting and stopping of the key coupler in the coupling position so that the amount keys may more easily be coupled thereto.

The illustrative machine is provided with a plurality of lock-controlled devices, one for each totalizer selecting key, for locking against operation one or both of the totalizer selecting keys and their corresponding totalizers.

One selecting key and its corresponding totalizer may be locked against operation by means of its respective lock-controlled device, and at such time means is provided for automatically selecting 15 the other totalizer and its associated devices for operation.

The present machine is also provided with separate locking mechanism, comprising adjustable control means under control of lock and key, which means when moved to a certain one of its various positions of adjustment is adapted to render ineffective not only the lock-controlled devices for the totalizer selecting keys, but simultaneously effect the automatic selection of 20 one of the clerks' totalizers and its associated 25 devices for operation.

When both of the clerks' keys are free to operate, means is provided for normally automatically selecting one of said totalizers and its associated devices for operation when any of the amount 30 keys alone are depressed.

Under the arrangement provided in applicant's machine, clerk "A" upon leaving the store may 35 lock his totalizer selecting key against operation, thereby preventing the selection of his totalizer and its associated devices for operation, and simultaneously effect the adjustment of the other totalizer and its associated devices for automatic 40 selection whenever any amount keys alone are depressed. Thus, it will be seen that the machine may be made to operate on an optionally "open" keyboard to register in either totalizer by simply locking against operation the selecting 45 key for the other totalizer.

Where machines are provided with lock-controlled devices for locking against operation the totalizer selecting keys and their corresponding totalizers, it sometimes becomes necessary for 50 the proprietor or other authorized persons to effect a registration in the totalizer of an absent clerk. To provide for this contingency, the adjustable means under control of lock and key, heretofore referred to, is adapted when moved 55 into a certain one of its various positions of adjustment to unlock either or both of the locked clerks' or totalizer selecting keys, even though they may have been locked by one or both of the clerks before leaving the store. The machine is 60 now in condition whereby the proprietor can effect registrations in either or both of the totalizers. When the locked clerks' keys are thus released, means is actuated for automatically 65 selecting the "A" totalizer and its associated devices for operation when any of the amount keys alone are depressed, while the "B" totalizer and its associated devices may be selected by the depression of the corresponding totalizer selecting key.

It will thus be seen that if one or both of the clerks' keys and their associated totalizers are locked against operation through their respective lock-controlled devices, movement of the adjustable means to a certain one of its various posi- 70

tions of adjustment will not only render ineffective said lock-controlled devices by releasing the locked clerks' keys, but will simultaneously and automatically condition the machine for operation on an optionally "open" keyboard to register in the "A" totalizer. When the adjustable means is moved from the position just referred to, the lock-controlled devices for the clerks' keys are again rendered effective.

10 It will be apparent that the adjustable means should be subject to the sole control of only the proprietor or manager of a particular store, and for this reason the adjustable means is provided with a lock to which the proprietor or manager is 15 the only one having a key.

Detailed description

The present machine is provided with a cash drawer casing 31 (Fig. 1), upon which is mounted 20 a suitable metal base 32, which serves as a support for two vertical side frames 33 and 34 (Fig. 10). These side frames are connected near the rear of the machine by a cross frame 35 and a tie bar 46 (Fig. 1) and at the front of the machine 25 by a tie bar 36. Near the center of the machine a pair of intermediate frames 37 and 38 (Fig. 10) are provided to support a number of totalizing and printing elements, as will be more fully explained hereinafter. The rear ends of these 30 intermediate frames are suitably supported by the cross frame 35, while their forward ends are connected to the tie bar 36.

The mechanism of the machine is enclosed in a suitable cabinet 39, provided with the usual 35 window (not shown) through which the indicators are visible. The portion of the machine which encloses the indicators is fully shown and described in the above mentioned patents. The contour of the cabinet is such as to properly 40 enclose all the operating parts, with the exception of a few elements which extend to the exterior of the cabinet for the purpose of operating the machine, and otherwise controlling it, as will be later explained.

Operating mechanism

The illustrative machine is of the key-operated 50 type of cash register and is provided with a number of keys divided into groups of amount keys 41 (Fig. 10) and a special group known as transaction keys 42. As all of the keys in each group are the same, it will suffice to illustrate and describe in this application but one key in each 55 group. In addition to these keys there is provided a plurality of special keys 43 and 44 known as "clerks" keys, the purpose of which is to control the selection of the totalizers and also act as coupler lifting keys.

The amount keys 41 and transaction keys 42 60 are pivoted upon a rod 45 (Figs. 1, 5, 6 and 10) extending transversely of the machine and journaled between the side frames 33 and 34. Resting upon the keys near their rear ends is a key coupler 47 journaled at 48 between the side frames. The key coupler has a flange or nose 49 cooperating at times with the usual notches (not shown) in the amount and transaction keys. When the outer ends of the keys are depressed 65 the key coupler 47 is rocked clockwise and the flange 49 thereon enters said notches. The purpose of such key coupler mechanism is old and well known in the art and need not be discussed herein.

Connected to the right-hand end of the key 70 coupler 47 is the usual vertical reciprocating rack 75

plate (not shown) which is provided with rack teeth which alternately mesh with a gear fast to the right-hand end of a shaft 50 to impart thereto a rotary motion. This mechanism is also old and well known in the art and as it is shown and described in the previously mentioned patents it is therefore not shown or described in this application.

Flexible-key coupler

As is usual in a machine of the type used for 10 illustration, there is provided a device for coupling amount or transaction keys to the key coupler at the beginning of their movement so that any desired number of keys may be successively depressed and coupled and then the depression of all of them completed by anyone to 15 effect the indication and registration of their combined value. This enables the operator to indicate and register with one hand a registration 20 requiring the operation of two or more keys since it obviates the necessity of spanning several keys with his hands in order to secure the simultaneous operation of those keys.

For the purpose of raising the key coupler 47 to 25 what is known as the "coupling point" any of the amount of special transaction keys may be employed, as above mentioned, but in the present instance the special keys designated as "clerks" 30 keys are especially provided to perform this function. The clerks' keys 43 and 44 (Fig. 10) are located at one end of the machine and are pivoted upon the rod 45 just as are the amount keys. Each clerk's key is formed with a notch 51 (Fig. 1) below the rear end of the key coupler. The forward edge of this notch is provided with a cam 35 surface 52 which engages a cam edge 53 of a notch cut in the under side of the key coupler. The notch 51 in each of the clerk's keys is adapted to receive the portion of the key coupler to the rear of the cam edge 53 when a clerk's key is depressed to its coupling position. An edge 55 of the notch 51 provides a stop face which engages the rearward edge of the flange 49 of the key coupler and positively stops the motion of the key and key 40 coupler. Thus when a clerk's key is depressed the cam edge 52 will cooperate with the cam edge 53 and raise the key coupler to a partially elevated position where it will be stopped by the engagement of the flange 49 with the edge 55 of the 45 notch 51 and will be held in this position by the usual full stroke mechanism, (not shown), but provided in machines of this type.

However, when pressure is removed from the clerk's key the rear end of the key will drop back until a finger 56 thereon rests upon the upper edge of an angular member 57 fastened to the key coupler. At this time, any of the amount 50 keys may be slightly depressed to engage them with and raise the coupler still further. During 55 this further operation the member 57 will be received by a cut-away portion 58 in the rear end of the clerk's key. This mechanism is shown and described more in detail in the patent to F. L. Fuller, No. 1,729,338, dated September 24, 1929, to 60 which reference may be made for a full showing and description thereof.

Differential mechanism

The differential mechanisms and devices controlled by each of the various banks of amount 70 keys are all similar in construction and operation so that a description of one will suffice for all.

Each of the amount keys is provided with an upwardly extending arm (not shown) carrying at 75

its extreme upper end a stud which cooperates with an L shaped slot 64 formed in a cam plate 65 (Fig. 1). The cam plates 65, of which there is one for each key in a bank, are carried by a frame 66 loosely pivoted upon a transverse shaft 67 journaled between the side frames 33 and 34. The slots 64 are arranged in graduated order so that their cooperation with their respective amount keys serves to move the frame 66 differential extents corresponding to the value of the key depressed. When the frame 66 is operated differentially by a key the studs associated with the undepressed amount keys in the same bank will play in arcuate portions of the slots 64 as shown in the Green Patent 1,842,546 to permit the upward tilting of the frame 66 without interfering with the studs carried by the unoperated keys.

It is to be understood that there is a differential frame 66 for each denominational group of amount keys. Each differential frame 66 has secured thereto and movable therewith a segmental rack 68 in constant engagement with a pinion (not shown) attached to the side of each item type carrier 69 mounted on a shaft 70 journaled at its ends in the intermediate supporting frames 37 and 38. Thus, it is evident that when the keys are depressed their corresponding racks 68 receive different degrees of movement so that the item type wheels 69 will be rotated correspondingly. When suitable impression means are actuated the item type wheels will print characters as shown in Fig. 10, indicating the amount of the transaction entered in the machine.

35

Totalizers

Located below the item type carriers 69 are two pivotally mounted totalizers, the upper of which is, for convenience, designated as the "A" totalizer and the lower as the "B" totalizer. These totalizers may be used for the purpose of registering amounts for separate departments or clerks or to segregate the transactions into any other two classes. The form of these totalizers is shown in 45 the patent to C. W. Green, No. 1,707,188, above referred to, and they are therefore not shown in detail here.

The "A" totalizer comprises a frame 71 (Fig. 1) pivotally mounted at 75 in the intermediate supporting frames 37 and 38 and carries a shaft 72 supporting a series of accumulating wheels 73, the peripheries of which are formed with raised characters so as to effect printing upon a record strip. Attached to the accumulating wheels 73 are pinions 74 (Fig. 10) which are adapted at times to be brought into mesh with the segmental racks 68 by rocking the totalizer frame 71 about its pivotal point 75 (Fig. 9).

The "B" totalizer, like the "A" totalizer, consists of a frame 76 (Fig. 8) carrying a shaft 77 supporting a series of accumulating wheels 78. Each wheel has attached thereto a pinion (not shown) adapted to engage its respective segmental rack 68. The totalizer frame 76 is journaled at 79 between the intermediate supporting frames 37 and 38 and is adapted to be rocked about this point to bring the pinions into and out of engagement with their respective segmental racks 68.

Totalizer selecting and engaging mechanism

Either one of the totalizers provided in the present machine may be selectively controlled for operation by means of the clerks' keys 43 and 44. 75 However, the "A" totalizer is adapted to be nor-

mally selected for operation so that when the amount keys alone are depressed the amount will be added into said "A" totalizer. In order to select the "B" totalizer for operation, the "B" key 43 must be depressed which not only disables the mechanism which normally selects the "A" totalizer, but selects for operation a special type carrier, indicator, special counter and cash drawer associated with the "B" totalizer.

When the "A" totalizer is selected for operation, mechanism is automatically operated which disables the "B" totalizer selecting means, and when the "B" totalizer is selected for operation means is provided for disabling the engaging mechanism associated with the "A" totalizer.

Pivotaly mounted upon a transverse shaft 80 (Figs. 1 and 9), located near the base of the machine, is a lever 81 carrying rollers 82 and 83 cooperating with a pair of complementary cams 84 and 85, secured to the main operating shaft 20 50. The lever 81 is connected to a bail 90 mounted on the shaft 80. Integral with the bail 90 is a forwardly extending lever 91 (Fig. 9) carrying a pin 92. The profile of the complementary cams 84 and 85 is such that the bail 90 and lever 91 are given an oscillating movement during each operation of the machine and this movement is utilized to effect the engagement of the selected totalizer with the actuating racks.

Adjacent the left supporting frame 37 are 30 totalizer engaging slides 93 and 94 (Figs. 1, 8 and 9). The "A" totalizer engaging slide 93 is provided with a cam slot 95 which engages the "A" totalizer supporting shaft 72. In a similar manner the "B" totalizer engaging slide 94 is provided with a cam slot 96 cooperating with the totalizer wheel supporting shaft 71 of the "B" totalizer. Both of these slides are apertured at their upper ends to engage the item type wheel supporting shaft 70, while at their lower ends the slides are 40 slotted at 97 and 98 to engage the stud 92 carried by the lever 91. Due to the above construction it will be evident that whenever a slide is reciprocated its cam slot cooperating with the associated totalizer wheel supporting shaft will rock the related totalizer about its pivot to bring the pinions into and out of engagement with the actuating racks 68.

Which one of the slides 93 or 94 is reciprocated is controlled by plates 99 and 100. Pivotaly mounted upon the pin 92 are two totalizer control plates 99 and 100 (Figs. 8, 9 and 12), the one associated with the lower or "B" totalizer indicated by the reference numeral 99 and the one associated with the "A" totalizer by the reference numeral 100. The plate 100 is provided with a cam slot 101 engaging a pin 102 carried by the "A" totalizer engaging slide 93. In a similar manner the "B" plate 99 is likewise provided with a cam slot 103 engaging a pin 104 carried by the "B" engaging slide 94. The configurations of the cam slots 101 and 103 is such that when either plate 99 or 100 is rocked about its pivot 92 from the normal position (shown in Figs. 8 and 9) it will tend to raise its associated slide 93 or 94. 65 The purpose of this mechanism is to neutralize the downward movement of the slide 93 or 94, as will appear later in the specification when the respective totalizer is not to be engaged.

Loosely mounted upon a shaft 105 are a plurality of throwout bails 106 and 107 associated respectively with the "A" and "B" totalizers. The bail 106 has integral therewith a downwardly extending arm 108 bifurcated at its lower end to receive a pin 109 carried by the cam plate 100. In 75

a similar manner the throwout bail 107 has integral therewith a downwardly extending arm 110 cooperating with a pin 111 on cam plate 99. Each of the bails 106 and 107 is provided with 5 rearwardly extending arms 112 and 113, respectively, to which are attached springs 114 and 115 which tend to retain the bails and cam plates in their normal positions, as shown in Figs. 8 and 9.

10 Associated with the "B" totalizer throwout bail 107 is a plate 120 (Fig. 1) provided with a shoulder 121 normally contacting a pin 123 attached to the side of the bail 107. The plate 120 is further provided with a cam edge coacting with a pin 122 15 projecting from the side of the "A" key 44. Pivotally mounted on the rod 45 (Fig. 5) adjacent and associated with the "B" key 43, is a lever 124 having a rearwardly projecting tail 125. Whenever the "B" key 43 is depressed the lever 124 is caused 20 to move in unison with said key by a pin 126 carried by the key 43 coacting with the underside of the tail 125 of the lever 124. A pin 127 in the lever 124 is adapted to coact with the forward cam edge of a cam plate 128 which is provided 25 with an extension 129 contacting the underside of the "A" throwout bail 106. From the above it will be noted that the "A" key 44, through its cam plate 120, operates the "B" throwout bail 107, while the "B" key 43, through the pin 127 in its 30 associate lever 124 and the cam plate 128, operates the "A" throwout bail 106.

Automatic engagement of "A" totalizer

The means for normally automatically engaging the "A" totalizer whenever any of the amount keys alone are depressed will now be described. A pitman 129 (Figs. 1 and 9) having a lower bifurcated portion 130 embracing the pin 92 is pivotally connected at its upper end to a plate 40 131 pivotally mounted on the shaft 105 and having a rearwardly projecting shoulder 132 adapted to contact with the underside of the "B" throwout bail 107. Loosely mounted on the pin 92 is a cam plate 133 having a cam slot 134 which 45 is adapted to cooperate with a pin 135 in the pitman 129. The cam plate 133 is connected to and adapted to move with the cam plate 100 by means of the pin 109. It will thus be evident that whenever the machine is operated by depression of any of the amount keys alone, the pin 92, through the cam plate 133, draws the pitman 129 downwardly and causes the shoulder 132 of the plate 131 to raise the "B" throwout bail 107. Raising the "B" throwout bail 107 (Fig. 50 8) rocks the arm 110 and the control plate 99 counterclockwise. The control plate 99, by its coaction with the stud 104, tends to shift the link 94 upwardly. But this upward movement of the link 94 is neutralized by the lowering of 55 the pin 92, which lowers the control plate 99 and, through stud 104, tends to lower the link 94. The rocking and lowering of the control plate 99 take place at the same time. The simultaneous rocking and lowering movements of the control plate 99 result in no movement of the slide 94, and therefore the "B" totalizer is not engaged 60 with the actuators when an amount key is depressed alone.

Should the "B" totalizer be selected for operation by depression of the "B" key 43, the arm 108 of the "A" throwout bail 106, through its engagement with the pin 109, moves the cam plates 100 and 133 counter-clockwise. The control plate 100 acting on the stud 102 tends to 65 shift the link 93 upwardly. But this upward

movement of the link 93 is neutralized by the lowering of the pin 92, which lowers the control plate 100 and, through the stud 102, tends to lower the link 93. The rocking and lowering movements of the control plate 100 take place 5 at the same time. The simultaneous rocking and lowering movements of the control plate 100 result in no movement of the link 93, and therefore the "A" totalizer is not engaged with the actuators when the "B" key is depressed. 10

The control plate 133 also has two movements simultaneously; i. e., it is rocked by the arm 108 and lowered by stud 92 at the same time. This combined rocking and lowering movement of the control plate 133 results in no movement of the 15 pitman 129, and therefore the arm 131 is not rocked to operate the "B" yoke 107, arm 110, and control arm 99. Therefore in this case the control plate 99 receives only the lowering movement, which, by its contact with stud 104, lowers 20 the slide 94 to engage the "B" totalizer with the actuators. 25

Clerks' key locks

The present machine is provided with individual locks for each of the clerks' or totalizer selecting keys 43 and 44, which directly control the operation or non-operation of the clerks' keys and their corresponding totalizers, each clerk being furnished with a key to the lock associated 30 with his particular totalizer selecting key. Such an arrangement makes it possible for each clerk to have full control of his totalizer and when going off duty he is enabled to lock his particular clerk's key and its corresponding totalizer against operation, without interfering with the 35 operation of the other clerk's key and its corresponding totalizer in the usual manner.

In the illustrative machine the "A" totalizer is normally automatically selected for operation, while special means is provided for automatically 40 selecting the "B" totalizer whenever the "A" totalizer is prevented from being operated by locking the "A" totalizer selecting key 44 against operation.

Mounted in a bracket 140 (Fig. 1) secured to the side frame 33 are locks 141 and 142, of conventional type, having barrels 143 and 144, respectively, projecting through slots formed in the cabinet 39 to facilitate the insertion of the keys in the locks. The lock 141 controls the operation of the "B" key 43, while the lock 142 controls the operation of the "A" key 44. 45

The means for locking the "B" key 43 against operation will now be described in detail. Pivotally mounted on a stud 145 attached to the side frame 33 is a lever 146 the upper end of which is adapted to coact with a bolt 147 of the lock 141 associated with the "B" key 43. The lower end of the lever 146 is formed in the shape of a hook 148 (Fig. 6) having a surface 149 adapted to contact a pin 150 on the "B" key 43. A spring 151 (Fig. 1), attached at one end to the lever 146 and at its opposite end to a stud 152 supported in the side frame 33, serves to maintain the lever 146 in contact with the bolt 147 of the lock 141. 55

In the normal positions of the parts, as shown in Fig. 6, the surface 149 is in the rear of the pin 150, so that it will not interfere with the depression of the key 43. Rocking of the lever 146 by rotating the lock barrel 143 counter-clockwise 60 to project the bolt 147 rearwardly carries the surface 149 thereof directly under the pin 150, thereby positively preventing depression of the "B" key 43. 65

The means for locking the "A" key 44 against 70

operation will now be described in detail. Loosely pivoted on the stud 145 are two levers 153 and 154 (Fig. 1) the upper end of the lever 153 being forked to provide a recess for a bolt 155 of the lock 142. Part of the lever 154 is shown by dot and dash lines in Fig. 6. This lever 154 lies in front of the lever 153 and is indicated by the dot and dash lines to give a better illustration of lever 153. The lower portion of the lever 154 is formed in the shape of a hook 152 having a surface 156 which is adapted to contact a pin 157 on the side of the "A" key 44. A spring 158 fastened at one end to a pin 159 carried by the lever 154 and secured at its opposite end to the stud 1152 normally retains the lower portion of the lever 154 and its surface 156 in a position just to the rear of the pin 157 on the "A" key 44. When the lock barrel 144 is turned the bolt 155 is projected rearwardly and rocks the lever 153 counter-clockwise thereby causing its lower portion to contact a pin 158 carried by the lever 154 and move the latter to bring its surface 156 beneath the pin 157 on the "A" key 44, thereby preventing the operation of the "A" key 44 and its corresponding totalizer. In this manner the "A" key 44 is locked against depression.

Automatic engagement of "B" totalizer

In order that the "B" totalizer be automatically selected by depression of the amount keys when the "A" totalizer is locked out, the lower end of the lever 153 is adapted to coact with mechanism for effecting the automatic selection of the "B" totalizer and its associated devices for operation when any of the amount keys alone are depressed. The lever 153 is bifurcated at its lower end to loosely straddle a stud 160 on a coupling slide 161 (Fig. 5). Loosely mounted on the shaft 80 is an arm 166 provided with a coupling slide 167 the upper end of which fits between a stud 168 on the rear bifurcated portion of the lever 153 and the stud 160 on the coupling slide 161 to normally cause the lever 153 and slide 161 to move in unison. The coupling slide 161 is provided with a slot 162 near its forward end through which projects the rod 45, while near its rear end the slide 161 carries a pin 163 which projects through a slot 164 in the lever 124 mounted on the rod 45 adjacent the "B" key 43. The coupling slide 161 is provided at its rear end with a hook portion 165 which, when the slide 161 is moved forwardly hooks over the flange 57 of the key coupler 47. Thus, when the machine is operated with the parts in these positions, the key coupler 47 raises the slide 161, together with the lever 124, and by means of the pin 127 on the lever 124 coacting with the cam plate 128 rocks the throwout bail 106 to prevent the engagement of the "A" totalizer, as previously described. In this way the "B" totalizer and its associated devices are automatically selected for operation when any of the amount keys alone are depressed.

Item printing mechanism

A suitable set of printing wheels is provided for printing the amount and character of the transaction, as well as the clerk making the entry, upon appropriate record material. Inasmuch as only one of these type wheels, the one adapted to print characters designating the clerks' keys, is involved here, only that portion of the mechanism will be described. For a more detailed showing and description reference may be had to the patent to Green, No. 1,920,374, previously referred to.

Referring to Fig. 7, there will be seen the clerk's printing wheel 69 which normally stands in a position to print the letter "A". Upon operation of the "B" key 43 or the lever 124 associated therewith this type wheel 69 is rotated to present the letter "B" to the printing line. The connections for this purpose comprise a pin 172 (Fig. 7) mounted on the side of the lever 124, associated with the "B" key 43, and adapted to cooperate with a cam slot in a plate 173 secured to one end 10 of a bail 174 loosely mounted on the shaft 80. The opposite end of the bail 174 carries an arm 175 to which is pivoted the lower end of a link 176 the upper end of the link 176 being connected to an arm 177 of a clamp 178 secured to a sleeve 179 15 mounted on the shaft 70. Rigid on the sleeve 179 is the clerk's type wheel 69. It will thus be clear that depression of the "B" key 43 or the automatic coupling of the coupler slide 161 with the coupler 47, through the raising of the lever 124 20 and its pin 172, rocks the plate 173 and arm 175 to elevate the link 176, thereby rocking the arm 177, clamp 178 and sleeve 179 to rotate the clerk's type wheel 69 to present the letter "B" to the printing line. 25

Shown directly above the clerk's type wheel 69 is a printing hammer 180 carrying a platen 181 near its forward end which is adapted, when the machine is operated, to take an impression from the clerk's type wheel upon suitable record material 182. This mechanism is fully shown and illustrated in the above mentioned patent to Green, No. 1,920,374, and therefore is not shown or described in detail here. 30

Special counters

The illustrative machine is provided with a series of consecutive number devices (Fig. 10) referred to herein as "special counters", which are adapted to register the total number of times the machine has been operated by each clerk. There is one special counter for each clerk's key. The special counters are arranged in a horizontal line at the front of the machine, just beneath the cabinet 39. These counters are of the regular 45 multi-tined pawl deep-notch transfer type, well known in the art and described in many patents, one of which is the patent to Thomas Carney, No. 876,295, patented January 7, 1908. Therefore, no full and complete showing or description of the 50 special counters will be given herein, as it is only the connections for operating the same which are involved in the present invention, which connections will be fully described. 35

The special counter associated with the "A" key 44, comprises a series of number wheels 187 (Fig. 10), each having attached to its side a ratchet 188 mounted on a shaft 189 supported at its ends in brackets 190, only the left hand one of which is shown secured to the tie bar 36. Loosely mounted 60 on the rod 189 (Figs. 4 and 11) is a bail 191 carrying a spring-pressed multi-tined pawl 192 mounted on a rod 193 supported at each end in the sides of the bail 191. When the bail 191 is rocked, the pawl 192 is adapted to engage the ratchets on the sides of the number wheels 187 and add a unit into the counter. The right-hand end of the rod 193 passes through and extends slightly beyond the right side of the bail 191 and is adapted to be engaged by a slotted arm 194 fast on a shaft 70 195 (Fig. 10). The shaft 195 is supported in the right-hand bracket (not shown, but like bracket 190) and in an ear (not shown) on the tie bar 36. Secured to the right-hand end of the shaft 195 is a cam arm 196 (Fig. 4) having a cam slot 75

197 adapted to cooperate with a stud 198 on the side of the upper end of an arm 199 rigidly secured to the side of the key coupler 41. It will thus be obvious that whenever the machine is 5 operated and the key coupler raised, the arm 196, through the stud 198 and slot 197 rocks the arm 196, the shaft 195 and the arm 194 counter-clockwise to rock the bail 191 and pawl 192 clockwise to add a unit into the special counter associated 10 with the "A" key 44.

The special counter associated with the "B" key 43 consists of a series of number wheels 204 (Figs. 1 and 10) each having attached to its side a ratchet 205 mounted on the shaft 189 adjacent 15 the special counter associated with the "A" key 44. Also loosely mounted on the shaft 189 is a bail 206 bearing a rod 207 carrying a spring-pressed multi-tined pawl 208 which is adapted, whenever the bail 206 is rocked clockwise, to engage the 20 ratchets 205 and add a unit into the "B" special counter. The rod 207 passes through and extends slightly beyond the left side of the bail 206 and is adapted to be engaged by a bifurcated arm 209 rigidly mounted on a shaft 210 supported by the 25 bracket 190 (Fig. 10) and ears 211 and 212 integral with the tie bar 36. Secured to the shaft 210 is a rearwardly extending arm 213. A link 214 connects the arm 213 to the lever 124 (Fig. 5) associated with the "B" key 43.

30 It will thus be evident that whenever the machine is operated with either the "B" key 43 depressed or the coupling slide 161 coupled to the key coupler 41, the forward end of the lever 124, through its connections with the key 43 and slide 35 161, is moved downwardly. Such downward movement of the lever 124, through the link 214 and arm 213, rocks the shaft 210 and arm 209 counter-clockwise, thereby rocking the bail 206 clockwise to engage the pawl 208 with the ratchets 205 and add a unit into the special counter associated 40 with the "B" key 43.

When the "B" counter is operated, means is provided for preventing the actuation of the wheels of the "A" counter. The means for accomplishing this consists of a pin 215 (Fig. 11) projecting from the left side of the pawl 192 of the "A" counter which is adapted to cooperate 45 with a disk 216 rigidly mounted on the right side of the bail 206 associated with the "B" counter. 50 When the bail 206 is rocked clockwise during an operation of the "B" counter, the disk 216 contacts the pin 215 and holds the pawl 192 disengaged from the ratchets 188 of the wheels 187 of the "A" counter.

55 *Indicating mechanism*

The machine disclosed in the present application is provided with indicating mechanism adapted to indicate to the front and to the rear, 60 not only the amount of the transaction but the clerk making the entry as well as the nature of the transaction being performed. Since only the mechanism actuating the clerks' indicators is involved here, only that mechanism will be 65 described.

The clerks' indicators comprise a series of flat tablets arranged in alignment one behind the other, bearing on their flat surfaces designations corresponding to the clerks' keys which they represent. The middle indicator tablet is stationary and bears on both its front and rear surfaces the letter "A" to correspond with the "A" clerk's key 44, which it represents. The remaining two indicator tablets, one of which is positioned in front 70 and the other in the rear of the "A" indicator

tablet bear on their outside surfaces the letter "B" to correspond with the "B" key 43, which they represent. The "B" indicator tablets are normally in unexposed position and when elevated to exposed position will completely conceal the stationary "A" indicator tablet from view. 5

The "A" indicator includes a tablet 219 (Fig. 10) integral with the upper end of a rod 220 (Fig. 1) which is loosely supported in guide plates 221 and 222 fast to the cross frame 35, in order to 10 prevent lateral movement of the indicator tablet. The "A" indicator tablet 219 rod 220 are held stationary by a notched plate 223 secured to an ear 224 integral with and projecting rearwardly from the rod 220, which notched plate 223 embraces a cross bar 225 supported at both ends in the cross frame 35. 15

The "B" indicator includes tablets 218 (Fig. 10) integral with the upper ends of rods 226 and 227 both of which rods are loosely supported 20 in the guide plates 221 and 222 to prevent lateral movement of the same. The rods 226 and 227, one on each side of the rod 220, are joined together by a pin 228 in order that they may be moved as a single unit. The rod 227 is longer than the rod 226 and is adapted to be elevated by the rear end of the lever 124, whenever the machine is operated to register in the "B" totalizer. It will thus be evident that when the "B" indicator rods 226 and 227 are elevated their 25 tablets 218 will completely conceal from view both sides of the "A" indicator tablet 219 and at the same time indicate that a transaction has been entered into the machine by the "B" clerk. The means for retaining the "B" indicator rods and their tablets in elevated positions and for releasing them during a subsequent operation is shown in the patent to Green, No. 1,920,374, heretofore referred to. 30

Drawer releasing mechanism

The present machine is provided with a plurality of cash drawers 234 and 235 (Fig. 2), one associated with each clerk's key. The reason for having a plurality of cash drawers in the machine is to provide a separate receptacle for each clerk, thereby enabling the proprietor to place individual responsibility for errors and shortages, and also to prevent one clerk from fraudulently withdrawing from the cash drawer money in charge of another clerk. The proprietor is able to learn whether the proper amount is in each clerk's cash drawer by comparing the cash in the drawer with the amount standing on the totalizer associated therewith. 45

The drawer 234 is assigned to the "A" clerk, while the drawer 235 is used by the "B" clerk. The "A" drawer 234 is normally selected to open when any of the amount keys alone are depressed, while the "B" drawer 235 is adapted to be selected and opened by the depression of the "B" key 43. However, locking of the "A" 50 clerk's key 44 against operation actuates means for effecting the automatic selection of the "B" cash drawer 235 when any of the amount keys 55 alone are depressed.

The cash drawers 234 and 235 (Figs. 1 and 2) are provided with latches 236 and 237, respectively, each of which latches is pivoted between a pair of lugs 238, only one of which is shown, 70 attached to the rear ends of the cash drawers. The rear ends of the latches 236 and 237 are normally drawn upward by coil springs 239 (only one of which is shown). The drawers 234 and 235 are held shut by the latches 236 and 237. 75

hooking over stationary bars 240 and 241, respectively, mounted in an auxiliary frame 242 secured to the base of the drawer casing 31. Associated with the latches 236 and 237 are levers 5 243 and 244, respectively, see also Fig. 3, pivoted at 245 and 246 to the auxiliary frame 242. The levers 243 and 244 are under tension of springs 247 and 248 and when rocked against the tension of such springs serve to release the latches 10 236 and 237 from the bars 240 and 241, respectively, thereby permitting their respective cash drawers to be ejected from the drawer casing 31 by means of the usual coil springs (not shown here).

15 The means for releasing the cash drawers comprises a vertical shaft 249 guided by a lug 233 of the auxiliary frame 242. The vertical shaft 249 carries a notched disk 250 having sections 251 and 252 which are adapted to cooperate 20 with the levers 243 and 244, respectively, to effect the release of the cash drawers 234 and 235. The section 251 is normally positioned directly under the inner end of the lever 243 associated with the latch 236 for the "A" cash drawer 234. 25 When the section 251 is in this position, the section 252 is positioned slightly to the rear of the lever 244 associated with the latch 237 for the "B" cash drawer 235. It will thus be seen that upon upward movement of the shaft 249 30 the section 251 of the disk 250 will contact with the end of the lever 243 and rock it to disengage the latch 236 from the bar 240, thereby releasing the "A" cash drawer 234. The means for moving the vertical shaft 249 upward will 35 now be described.

The upper end of the shaft 249 extends through an apertured lug 254 formed at the lower end of a link 253. Mounted on the shaft 249 is a fixed collar 271 against which the lug 40 254 bears when the shaft 249 is lifted upwardly. The upper end of the link 253 is connected to a lever 255 pivoted to a lug 256 integral with the base 32. Pivoted to the lever 255 is a by-pass pawl 257 which is normally spring pressed against 45 a pin 258 on the lever 255 by a compression spring 259 extending between the pawl 257 and a lug 260 on the lever 255. The key coupler 47 is provided with a depending projection 261 which, when the coupler is raised during an 50 operation of the machine, bears against and rocks the pawl 257 until it clears the top of the pawl, thus permitting the pawl to return to its normal position. As the key coupler 47 descends, upon the up stroke of the keys, the projection 55 261 contacts the upper end of the pawl 257 and the pawl and the pin 258 rock the lever 255 clockwise to raise the link 253 and lift the vertical shaft 249. When the shaft 249 is thus lifted, the section 251 of the notched disk 250 60 contacts and moves the lever 243 against the tension of the spring 247, thereby releasing the latch 236 for the "A" cash drawer which is then ejected from the casing by the usual coil spring.

The means will now be described for effecting 65 the release of the "B" cash drawer 235. Pivotally mounted at 262 (Fig. 1) to a bracket (not shown) secured to the auxiliary frame 242 is a lever 263 the upper end of which cooperates with pins 264 and 265 mounted on the lever 124 associated with the "B" key 43. The lower end of the lever 263 extends through an opening in one end of a lever 266 pivoted at 267 to a bracket 268 secured to the auxiliary frame 242. The other end of the lever 266 carries a downwardly extending 70 pin 269 which is engaged by a bifurcated arm 270

fast to the lower end of the vertical shaft 249.

It will thus be seen that when the rear end of the lever 124 associated with the "B" key 43 is raised, the pins 264 and 265 rock the lever 263 counter-clockwise which rocks the lever 266 and the latter rotates the arm 270 and shaft 249 clockwise (Fig. 3). Such clockwise movement of the shaft 249 moves the section 251 of the disk 250 from beneath the lever 243 and moves the section 252 directly under the lever 244 associated with the "B" cash drawer 235. It will, therefore, be apparent that when the shaft 249 is lifted upwardly, with the section 252 positioned directly under the lever 244, the lever 244 will be rocked against the tension of its spring 248 to release the latch 15 237 from engagement with the bar 241, thereby causing the "B" cash drawer 235 to be opened. Upon return of the lever 124 to normal, the pins 264 and 265 return the lever 263 and associated parts to normal. 20

Adjustable control means

As hereinbefore mentioned, each of the clerk's keys is provided with an individual lock whereby the clerks, when going off duty, may lock their respective keys against operation. Should all of the clerks happen to be off duty at a particular time and the machine be locked against operation by the clerks' key locks above mentioned, the proprietor would be unable to depress the keys and operate the machine in the usual manner without using duplicate keys to the clerks' key locks. To enable the proprietor to have complete control over the clerks' keys when they are locked against operation, adjustable control 35 means is provided which when moved to a certain one of its various positions of adjustment will not only release the locked clerks' keys for operation but will effect the automatic selection of the "A" totalizer and its associated devices for operation 40 whenever any of the amount keys alone are depressed.

Pivotaly mounted on the key rod 45 (Figs. 1 and 6) is a bell crank 277, an upwardly extending arm 278 of which is provided with a stud 279 45 of sufficient length to engage shoulders 280 and 281 on the lower portions of the locking levers 146 and 154, respectively. Secured to the shaft 80 is a cam 282 in the path of the lower arm of the bell crank 277. When the shaft 80 is rotated 50 the stud 279 contacting with the shoulders 280 and 281 of the locking levers 146 and 154 forces said levers counter-clockwise until the arcuate slots therein are in the paths of the studs 150 and 151 carried by the clerks' keys 43 and 44, respectively. When the parts are in these positions the clerks' keys may be depressed irrespective of whether both of the bolts 147 and 155 of the clerks' key locks have been projected to effect the locking of said keys against operation. 55

The shaft 80 and cam 282 are rotated by adjustable control means comprising a lever 283 pivoted on the shaft 67 (Fig. 6). The lever 283 has formed at its lower end a gear sector 284, while at its upper end it is provided with a rearward extension 285 and a forward extension 286. The extension 286 carries a shouldered stud 287 adapted to coact with the upper edge of a notched plate 288 secured to the side frame 34, for the purpose of keeping the lever 283 in alignment 65 with the notched plate 288 whenever it is moved to its various positions of adjustment. Fastened to the extension 285 is a lock 289 having a rotatable barrel 290 fast to the lower end of which is a locking arm 291. Pivoted at 292 on the lever 283 is 70 75

a retaining pawl 293 carrying a stud 294 which is normally spring-pressed into engagement with any one of a series of notches formed in the under side of the notched plate 288 by means of a spring 5 295 fast at one end to the pawl 293 and at its opposite end to an ear 296 formed in the lever 283. Each one of the notches formed in the plate 288 represents a different position of adjustment of the lever 283. The stud 294 on the 10 pawl 293 is adapted to ratchet in and out of the notches of the plate 288 and thereby act as a retainer for the lever 283 when it is moved to each of its various positions of adjustment.

The lever 283 may be locked in any one of its 15 various positions of adjustment by a key 297 for the lock 289. Turning the key in a clockwise direction rotates the barrel 290 and locking arm 291 clockwise to a point where the locking arm 291 is positioned directly above finger 298 on the 20 retaining pawl 293. It will thus be evident that should an attempt be made to move the lever 283 to another position of adjustment the stud 294 is prevented from moving out of its engaged notch by the contact of the finger 298 with the locking arm 291. The barrel 290 of the lock 289 is so constructed that the key 297 cannot be removed therefrom unless the barrel is in locking position, thus making it necessary to always lock the lever 283 in one of its positions of adjustment 25 before removal of the key from the lock can be effected.

Provided on the outside surface of the cabinet 39, adjacent a slot (not shown) through which the lock barrel 290 attached to the control lever 283 35 projects, is an index identifying the various positions of adjustment to which the lever 283 may be moved. This index is represented in the drawings (Fig. 6) by the notations designating various notches in the plate 288.

When the lever is moved to its uppermost position, identified by the word "Reset," the machine is conditioned for printing the totals standing on the totalizers and resetting the totalizers. When the lever is moved to the "Unlock A & B" 40 position the locked clerks' keys are released for operation and the machine is conditioned for automatic selection of the "A" totalizer and its associated devices for operation whenever any of the amount keys alone are depressed. When the lever is moved to the "Closed drawer" position the machine is conditioned so that it cannot be operated unless the cash drawers are closed. With the lever in the "Open drawer" 45 position the machine is conditioned so that it can be operated while the cash drawers are open. When the lever is moved to its "Lock register" position the machine is locked against operation.

When the lever 283 is moved to the "Unlock A & B" position, the locked clerks' keys are released for operation and the "A" totalizer and its associated devices are automatically selected for operation whenever any of the amount keys alone are depressed. The means for accomplishing this will now be explained in detail.

60 Mounted loosely on the key rod 45 is a gear sector 304 meshing with the gear sector 284 on the lever 283, and secured to the gear sector 304 is a gear 305 meshing with a gear 306 secured to the right hand end of the shaft 80 65 hereinbefore mentioned. From the foregoing it is evident that when the proprietor manipulates the lever 283 so that it is set in the "Unlock A & B" position the shaft 80 will be rocked by the train of mechanism just described to actuate 70 the cam 282 to disable the locking levers 146 and

154, thereby releasing any locked clerks' keys 43 and 44.

As previously mentioned, the machine is normally conditioned for automatic selection of the "A" totalizer and its associated devices for operation when any of the amount keys alone are depressed. However, the locking of the "A" totalizer selecting key 44 against operation renders effective means for automatically selecting the "B" totalizer and its associated devices. 10 When both of the clerks' keys 43 and 44 are locked against operation, it is necessary to provide means, under the control of the lever 283, when it is moved to its "Unlock A & B" position, to render ineffective the means for automatically selecting the "B" totalizer and its associated devices, in order to permit the normal automatic selection of the "A" totalizer and its associated devices. The means for accomplishing this result will now be described in detail. 15

Secured to the shaft 80 is a box cam 307 (Fig. 5) provided with a raceway 308 cooperating with a stud 309 carried by the rearwardly extending arm of a bell crank 310 pivoted on a rod 311 supported in the side frames 33 and 34. When 25 the lever 283 is moved to its "Unlock A & B" position, it rotates the shaft 80 counter-clockwise, through the train of gear mechanism previously mentioned (Fig. 6), and thereby causes the box cam 307 to rotate counter-clockwise (Fig. 5). 30 Such movement of the cam 307 rocks the bell crank 310 counter-clockwise. The bell crank 310 has an ear 315 carrying a pin 314 cooperating with a slot 316 in the arm 166. The coupling slide 167 is tapered at its upper end to provide 35 sufficient clearance for the stud 160 so that the slide 161 can be adjusted by the lever 283 independently of the lever 153. Therefore, when the bell crank 310 is rocked counter-clockwise, the arm 166 is rocked clockwise to lower the coupling 40 slide 161 to a point where its tapered end permits sufficient clearance for the stud 160 to be moved rearwardly by the upwardly extending arm of the bell crank 310 to uncouple the slide 161 from the key coupler 41. In this manner the 45 automatic selection of the "B" totalizer and its associated devices is prevented, and the machine is conditioned for automatic selection of the "A" totalizer and its associated devices.

Operation

50

A summary of the operation of the above described devices and the manner in which they operate so as to enable the machine to be operated on an automatic "open keyboard" with respect to registering in one totalizer, and on an optionally "open keyboard" with respect to registering in another totalizer, will now be given. 55

The illustrative machine is provided with two totalizers, each of which has associated therewith a totalizer selecting key. A plurality of lock-controlled devices is provided, one for each totalizer selecting key, for locking the keys and their associated totalizers against operation.

In the present machine the "A" totalizer and 65 its associated devices are normally automatically selected for operation whenever the machine is operated by depression of any of the amount keys alone, thus permitting the machine to be operated on an automatic "open keyboard" with 70 respect to the "A" totalizer and its associated devices.

The "B" totalizer and its associated devices are normally selected by depression of its corresponding totalizer selecting key. However, auto- 75

matic selection of the "B" totalizer and its associated devices may be effected by simply locking the "A" totalizer selecting key, through its respective lock-controlled device, against operation. Under such an arrangement the machine may be operated on an optionally "open keyboard" with respect to the "B" totalizer and its associated devices.

From the above it will be apparent that when one totalizer is locked against operation, through the lock-controlled device for its respective totalizer selecting key, it effects the automatic selection of the other totalizer and its associated devices for operation whenever the machine is operated by depression of any of the amount keys alone.

From the foregoing it is apparent that the illustrative machine is especially adapted for use in places of business operating on both day and night shifts. For example, the "A" totalizer may be assigned to the clerk employed on the day shift, while the "B" totalizer may be used by the clerk employed on the night shift. The lock-controlled devices for the totalizer selecting keys enable each clerk, when going off duty, to lock his particular totalizer selecting key and associated totalizer against operation, thereby preventing any registration being made in his particular totalizer or access to his cash drawer, during his absence. Inasmuch as the "A" totalizer and its associated devices are normally automatically selected for operation, the clerk on the day shift may operate the machine on an automatic "open keyboard" with respect to registering in his particular totalizer. When the day clerk goes off duty, he locks his totalizer selecting key and corresponding totalizer against operation, such locking operation also serving to condition the machine for automatic selection of the "B" totalizer and its associated devices. When the clerk employed on the night shift comes on duty, he unlocks his particular totalizer selecting key, thereby releasing the machine for operation on an automatic "open keyboard" with respect to the "B" totalizer and its associated devices.

It sometimes happens that both clerks are absent at a particular time and their totalizer selecting keys are locked against operation, through the lock-controlled devices associated therewith, thus locking the machine against operation. On such occasions the proprietor or other authorized person sometimes wishes to register an amount into the machine. In order to enable the proprietor or other authorized person to make such a registration, without the necessity of using duplicate keys to the totalizer selecting key locks, the adjustable control means, under control of lock and key, when moved to its "Unlock A & B" position is adapted to release the locked totalizer selecting keys and effect the automatic selection of the "A" totalizer and its associated devices for operation whenever the machine is operated by depression of any of the amount keys alone. Under this arrangement, the machine may be operated on an automatic "open keyboard" with respect to registering in the "A" totalizer, while depression of the "B" totalizer selecting key is necessary to select the "B" totalizer for operation.

While the form of mechanism herein shown and described is admirably adapted to fulfill the objects primarily stated, it is to be understood that it is not intended to confine the invention to the one form of embodiment herein disclosed, for it is susceptible of embodiment in various

forms all coming within the scope of the claims which follow.

I claim:

1. In a machine of the class described, the combination of a plurality of totalizers; actuating mechanism therefor; engaging mechanism for engaging the totalizers with the actuating mechanism, a plurality of keys adapted to condition certain elements of the engaging mechanism for controlling the engagement of said totalizers with said actuating mechanism; a plurality of individual lock-controlled devices one for each of said keys adapted to lock said keys against operation; and means controlled by one of said devices when operated to lock its associated key and for automatically conditioning the engaging mechanism to cause the totalizer associated with the other key to be engaged with the actuating mechanism upon operation of the engaging mechanism.

2. In a machine of the class described, the combination of a plurality of totalizers; actuating means therefor; engaging mechanism for engaging the totalizers with the actuators; a plurality of keys to condition certain elements of the engaging mechanism to control the engagement of the totalizers; a plurality of lock-controlled devices one for each key for controlling the operation of its associated key and corresponding totalizer; and means adapted to condition the engaging mechanism to automatically engage one totalizer for actuation when the key for another totalizer is locked against operation.

3. In a machine of the class described, the combination of a plurality of totalizers; a totalizer engaging mechanism; a plurality of keys to condition the engaging mechanism for selectively engaging a totalizer; a plurality of lock-controlled devices each of which is adapted to lock one of said keys against operation; and means operated by one of said lock-controlled devices to condition the engaging mechanism to effect automatic engagement of one of said totalizers.

4. In a machine of the class described, the combination of a plurality of totalizers; a totalizer engaging mechanism; a plurality of keys to condition the engaging mechanism to engage a totalizer; a plurality of lock-controlled devices each of which is adapted to lock one of said keys against operation; a key coupler; a coupling slide; means operated by one of said lock-controlled devices for coupling said slide to said key coupler whereby the coupling slide is actuated by the key coupler; and means actuated by the coupling slide to effect automatic engagement of one of said totalizers.

5. In a machine of the class described, the combination of a plurality of totalizers; totalizer engaging means; a plurality of keys to condition the engaging means to selectively engage the totalizers; a plurality of lock-controlled devices each of which is adapted to lock one of said keys against operation; a key coupler; a coupling slide; a lever connected to said slide by a pin and slot connection; means operated by one of said lock-controlled devices for coupling said slide to said key coupler whereby the coupling slide and lever are connected to the key coupler for actuation thereby; and connections between the lever and the engaging mechanism to control the engaging mechanism to effect an automatic engagement of one of said totalizers.

6. In a machine of the class described, the combination of a plurality of totalizers; totalizer engaging means; a plurality of keys to condition

the engaging means to selectively engage the totalizers; a plurality of lock-controlled devices one for each key for locking said keys against operation; a key coupler; a coupling slide; a rockable member intermediate said slide and one of said keys; means operated by one of said lock-controlled devices for coupling said slide to said key coupler; connections between the rockable member and the slide whereby the slide actuates the rockable member upon actuation of the key coupler; and connections between the member and the engaging means whereby the member controls the engaging mechanism to effect automatic engagement of one of said totalizers.

15 7. In a machine of the class described, the combination of amount keys; a plurality of totalizers; mechanism to normally engage one of said totalizers for actuation upon operation of any of said amount keys; means to render said mechanism ineffective; and a device operable as a preliminary to an operation of the machine to supersede the control of said rendering means and to condition said mechanism to normally engage said one totalizer for actuation upon operation of said amount keys.

8. In a machine of the class described, the combination of amount keys; a plurality of totalizers; automatically operated devices for engaging one of said totalizers for actuation upon operation of any of said amount keys; means to render said operated device ineffective; a manipulative member; mechanism controlled by said manipulative member for rendering said means ineffective; another manipulative member; and means controlled thereby for rendering said mechanism ineffective.

9. In a machine of the class described, the combination of amount keys; a plurality of totalizers; means to automatically engage one of said totalizers for operation upon operation of

any of said amount keys; means operable as a preliminary to an operation of the machine for rendering said automatic engaging means ineffective and for simultaneously conditioning the machine to automatically engage another of said totalizers for operation upon operation of any of said amount keys; manipulative means to supersede the control of said second mentioned means whereby said one totalizer may be again automatically engaged for actuation upon operation of said amount keys; another manipulative means adapted when operated in conjunction with said first mentioned manipulative means to condition the machine to engage said another of said totalizers for actuation upon operation of any of said amount keys.

10 10. In a machine of the class described, the combination of amount keys; a totalizer adapted to be normally engaged for actuation upon operation of any of said amount keys; a second totalizer; a lock for locking the first totalizer against actuation; means controlled by the lock for conditioning the machine for automatic engagement of the second totalizer upon operation of any of the amount keys; a lock for the second totalizer; a member having a plurality of positions of adjustment; mechanism controlled by said member when it is moved into a certain one of its positions for rendering the means controlled by the first lock ineffective and for simultaneously conditioning the machine for automatic engagement of the first totalizer upon operation of any of said amount keys; a manipulative device; and means controlled by said manipulative device when the latter is operated in conjunction with said member to condition the machine for engagement of said second totalizer upon operation of any of the amount keys.
